[57] CLAIM

The ornamental design for a cushion for use in a child's seat of a shopping cart, as shown and described.

DESCRIPTION

FIG. 1 is a front view of a cushion for use in a child seat of a shopping cart, showing my new design;

FIG. 2 is a rear view thereof;

FIG. 3 is a right side view of the cushion shown as applied to a child's seat of a shopping cart;

FIG. 4 is a top plan view of FIG. 3;

FIG. 5 is a left side view of FIG. 3; and,

FIG. 6 is a perspective view of FIG. 3.

The cross-hatching represents conventional fabric and is understood to extend uniformly throughout the areas represented.
